DESIGN FOR A FENDER FOR A CYCLE

Herman L. Kraeft, Cleveland Heights, Ohio, assignor to The Murray-Ohio Manufacturing Company, Cleveland, Ohio, a corporation of Ohio

Application September 17, 1936, Serial No. 64,891

Term of patent 7 years

To whom it may concern:

Be it known that I, Herman L. Kraeft, a citizen of the United States, residing at Cleveland Heights, in the county of Cuyahoga and State of Ohio, have invented a new, original, and ornamental Design for a Fender for a Cycle, of which the following is a specification, reference being had to the accompanying drawing, forming a part thereof.

In the drawing, Fig. 1 is a side elevation of a fender for a cycle, showing my new design; Fig. 2 is a perspective view of the same; and Fig. 3 is a transverse sectional view taken as indicated by the lines 3—3 on Fig. 1.

I claim:

The ornamental design for a fender for a cycle substantially as shown.

HERMAN L. KRAEFT.
